FOLDING TABLE

William P. De Saussure, Jr., Englewood, N. J.

Application February 15, 1939, Serial No. 256,433

12 Claims. (Cl. 311—88)

This invention relates to folding tables of the type in which either the tops of the legs or the upper ends of the leg bracing links are slidably connected to the table top to permit the legs 5 to be extended or retracted. The object of the invention is to provide improved means for locking the legs in extended position of simple construction, positive and reliable in action, and readily releasable when the legs are to be folded.

According to the invention, the sliding connection with the table top of the upper ends of the legs, or of the upper ends of the bracing links, as the case may be, is by means of rotatable lugs extending from the leg ends, or link 15 ends, into guiding slots, the lugs being of greater thickness in one direction than in another and the slots being of a width less than the greater thickness of the lugs and having enlarged parts at the points reached by the lugs when the legs 20 have been moved to their extended position. When the legs have been moved to their extended position each of the lugs is turned in the enlarged part of its slot to an angular position such that it cannot re-enter the smaller 25 part of its slot, whereby the leg is securely locked in position. The legs are usually connected in pairs, and in such case the guiding and locking lugs for each pair of legs are most desirably formed by the ends of a rod which extends between and is rotatably connected to the legs, and, most desirably, the turning movement of 30 this rod to locking position is effected automatically, as by means whereby, as the legs move to their extended position, the rod is put under tension to turn its ends to locking position when 35 they have reached the enlarged part of the slots.

A full understanding of the invention can best be given by a detailed description in connection with drawings illustrating approved embodiments of the same, and such a description will now be given in connection with the accompanying drawings, in which:

Fig. 1 is a side elevation of one end of a table embodying my invention, with the legs shown in folded position in full lines and by dotted lines in partly extended position;

Fig. 2a is an enlarged perspective view showing the crossing of the cross braces between the table legs and the plate by which they are bound together;

Fig. 2 is a bottom plan view of the same with the legs folded;

Fig. 3 is an end elevation of the same with the legs folded;

Fig. 4 is a section on the line 4—4 of Fig. 2 but showing the leg partly extended;

Figs. 5 and 6 are broken side views showing the relationship between the pivot pin and its slot as the legs approach and reach their extended 5 position;

Fig. 7 is an end elevation of the table with parts in section, the legs being in partly extended position as in Fig. 4;

Fig. 8 is an end elevation of a table embodying 10 ing in a modified form certain features of the invention;

Fig. 9 is a section on the line 9—9 of Fig. 8 with the pivot pin turned into release position;

Fig. 10 is a side elevation of the table shown 15 in Fig. 8 taken in the direction of the arrow 10 of Fig. 8;

Fig. 11 is a side elevation of a table embodying certain features of the invention in another modified form;

Fig. 12 is a section on the line 12—12 of Fig. 11; 20 and

Fig. 13 is a section on the line 13—13 of Fig. 12.

Referring to the drawings, and first to Figs. 1 to 7, the table top 15 has secured to its under side at each end, only one end of the table being shown in Figs. 1 and 2, two spaced angle bars 16. The vertical downwardly projecting web of each of these angle bars has near its outer end a longitudinally extending slot 17. A pair of table legs 18 connected at their upper ends by an angle bar 19 are pivotally and slidably connected to the table top by a rod 20 which extends between the upper ends of the legs and through openings in the upper ends and has its two ends extending into the guiding slots 17. A bracing and positioning link 21 for each leg is pivotally connected at its upper end to one of the bars 16, as indicated at 22, and at its lower end to the leg at a point 23 suitably distant from the upper end of the leg, so that when the lower ends of the legs are moved downward away from the table top the upper ends will move inward away from the end of the table, the guide lugs formed by the ends of the rod 20 sliding in the guide slots 17 30 until the lugs reach the inner ends of the slots, at which time the legs will be in their vertical extended position. The angle bars 16 are spaced apart sufficiently to leave room between the bars and the legs when in closed position for the 35 links 21, and spacing washers 26 are provided on the rod 20 between the ends of the legs and the angle bars.

As shown, the legs are braced by means of cross braces 24 formed by flat metal strips op- 40 45 50 55 60 65 70 75 80 85 90 95 100 105 110 115 120 125 130 135 140 145 150 155 160 165 170 175 180 185 positely notched at the crossing point and bound together by a pair of plates 25 welded to the braces one on each side thereof, the plates having turned-over edges or flanges and being of such dimensions that these flanges engage the sides of the cross-bars.

The rod 20 most desirably and as shown is a round bar of steel or other suitable elastic material, and the ends of the bar beyond the ends 10 of the legs are flattened, as by being cut away on one side, as most clearly shown in Figs. 5 and 6, so that the thickness of the ends in one direction is less than the diameter or thickness of the bar; and the slots 17 are narrower than the diameter of the bar and most desirably of a width 15 just sufficient to take the ends of the bar with an easy sliding fit when the bar is turned so that the flat sides of the ends are parallel with the edge of the slot, as shown in Figs. 1 and 5, except that 20 at its inner end each of the slots has an enlargement which is of circular form and of a size to receive the ends of the rod when turned to any angular position, or to receive the unreduced cylindrical rod. When the legs are in folded position and during the opening and closing movements 25 of the legs with the ends of the rod travelling in the slots, the flat sides of the rod ends are parallel to the edge of the slot. When the legs are in their fully extended position, the ends 30 of the rod are in the enlarged end portions of the slots, and may then be turned to an angular position such as shown in Fig. 6, and when so turned the legs are thereby securely locked in extended position, since when the rod ends are 35 so turned it is impossible for them to re-enter the narrower portion of the slots.

In order to prevent endwise movement of the rod after assembly when its ends are in the enlarged end portions of the slots, the holes in the 40 spacing washers 26 are of the segmental form of the ends of the rod 20 and thus serve as retaining means, holding the rod against such movement.

In the table shown in Figs. 1 to 7, the turning 45 of the rod 20 to lock the legs when they have been swung out to their extended position is effected automatically. For this purpose, the rod 20 is provided with a bent plate 27 welded or otherwise attached thereto at the middle thereof, and one end of this plate 27 extends in position 50 to engage an edge of the angle bar 19 so that as the legs are swung outward away from the table and their upper ends moved inward from the end of the table, the angle bar, as the legs pivot 55 on the rod 20, forces the engaged end of plate 27 upward; and since the ends of the rod cannot turn in the slots 17 until they reach the enlarged inner end of the slots, the middle portion 60 of the rod is turned slightly and forced upward as shown in Fig. 4 and by dotted lines in Fig. 5, thus putting the ends of the rod under torsional strain so that when the rod ends are moved into the enlarged end portions of the slots the ends 65 turn to the angular position shown in Fig. 6. With the rod ends in this angular position they cannot re-enter the slots, and the legs are thus securely locked in their extended position.

When the rod 20 is in locking position, the inwardly extending end of the plate 27 is turned 70 down away from the table top, as shown in Fig. 6, and this end of the plate serves as means whereby, by pressing it upward toward the table top, the rod may be turned back to bring the flat side of its ends into alignment with the edge 75 of the slots, thereby unlocking the legs, the rod

ends being then in angular position to enter the slots and be slidable therein to permit the legs to be returned to folded position. This plate end, or finger-piece, extends at such an angle and for such distance from the rod that when it has been moved upward into engagement with the table top the rod ends are in the right angular position to enter the slots, the part of the table top engaged by the finger piece serving as a stop to limit the movement of the finger-piece.

In the modification shown by Figs. 8, 9 and 10, instead of depending on the use of a spring rod which is put under torsional strain for effecting the locking movement of the rod ends when the legs reach their extended position, a cross-bar 30 connecting the upper ends of the legs carries a leaf spring 31 which bears against a lug or shoulder on the pivot rod 20a, such lug being formed, as shown, by one end of a plate 27a welded to the rod. As the upper ends of the legs move inward when the legs are being swung out to extended position, the spring 31 is put under tension so that when the ends of the rod come to the enlarged ends of the slots the rod is turned by the spring to effect the locking of the legs as before. As shown in this figure, also, the rod ends are flattened on their upper side instead of on the lower side as in Figs. 1 to 7, and the enlargement at the inner end of the slots is not of complete circular form, so that, the reduced end portions of the rod being suitably short, the angle bars 16 serve to prevent endwise movement of the rod out of position after assembly, and the spacing washers 26 are not depended on for this purpose and may have circular holes therein.

Figs. 11, 12 and 13 illustrate an embodiment of the invention in a table in which the legs have a fixed pivoted connection and the bracing and positioning links a sliding connection to the table top, and the locking is effected manually. The locking rod 20b extends between and through the upper ends of the links 21b and its flattened ends extend into the slots 17b of the angle bars 16b. The locking enlargements are at the outer end of the slots, that is, the end toward the leg pivots, and as shown are not circular but of a form such as shown in Fig. 10, so that the unreduced portions of the rod cannot pass through them. The flattened portion of the rod end shown is made by milling or otherwise forming a slot in the rod, leaving unreduced the end portion extending beyond the flattened portion. This extending end has welded thereon a plate 40. By pressing on one or the other ends of this plate 40, the rod may be given the necessary turning movement for locking and unlocking the legs when they are in extended position and the rod ends in the locking enlargements of the slots 17b. Such an operating plate might obviously 55 be applied to the other end of the rod, also, and in such case these plates will serve to prevent endwise movement of the rod out of position, one of the plates being welded to the rod end after assembly. For convenience in assembly when 60 the locking enlargements of the slots 17b are, as shown, not of a size or shape to permit the unreduced portions of the rod to pass, the slots 17b may be extended at their other ends for a distance beyond the path of travel of the ends of 65 the locking rod and provided in such extended portion with an enlargement 41 of sufficient size to permit the unreduced portions of the rod to pass through.

What is claimed is:

5 a shoulder on said rod, and a part moving with the legs which engages said shoulder and applies pressure thereto as the legs are swung out to their extended position to put the rod ends under torsional strain whereby when they enter the enlarged part of the slots they are turned to lock the legs in extended position.

9. The combination in a folding table, of a pair of connected legs, a bracing and positioning link pivotally connected to each of said legs intermediate the ends of the leg, the upper ends of said links being pivotally connected to the table top and the upper ends of the legs being pivotally and slidably connected to the table top by means of a rod extending between and rotatably connected to the upper ends of the legs and extending beyond the end of the leg into slots in members connected to the table top, the ends of said rod which lie in said slots being of greater thickness in one direction than in another and said slots being of a width less than the greater thickness of the ends of the rod and each having an enlarged part at the point reached by the end of the rod when the legs are in extended position, a shoulder on said rod, and a spring tensioned by movement of the legs to their extended position and which acts to give the rod a partial turn when its ends enter the enlarged part of the slots to lock the legs in extended position.

10. The combination in a folding table, of a pair of connected legs, a bracing and positioning link pivotally connected to each of said legs intermediate the ends of the leg, the upper ends of said links being pivotally connected to the table top and the upper ends of the legs being pivotally and slidably connected to the table top by means of a rod extending between and rotatably connected to the upper ends of the legs and extending beyond the end of the leg into slots in members connected to the table top, the ends of said rod which lie in said slots being of greater thickness in one direction than in another and said slots being of a width less than the greater thickness of the ends of the rod and each having an enlarged part at the point reached by the end of the rod when the legs are in extended position, a shoulder on said rod, and a spring tensioned by movement of the legs to their extended position and which acts to give the rod a partial turn when its ends enter the enlarged part of the slots to lock the legs in extended position.

11. The combination in a folding table, of a pair of connected legs, a bracing and positioning link pivotally connected to each of said legs intermediate the ends of the leg, the upper ends of

5 said links being pivotally connected to the table top and the upper ends of the legs being pivotally and slidably connected to the table top by means of a rod extending between and rotatably connected to the upper ends of the legs and extending beyond the end of the leg into slots in members connected to the table top, the ends of said rod which lie in said slots being of greater thickness in one direction than in another and said slots being of a width less than the greater thickness of the ends of the rod and each having an enlarged part at the point reached by the end of the rod when the legs are in extended position, means whereby by movement of the legs to their extended position said rod is put under tension to turn its ends when they enter the enlarged part of the slots to lock the legs in extended position, and a finger-piece extending from the rod and having a limited movement whereby the rod may be turned to unlock the legs.

12. The combination in a folding table, of a pair of connected legs, a bracing and positioning link pivotally connected to each of said legs intermediate the ends of the leg, the upper ends of said links being pivotally connected to the table top and the upper ends of the legs being pivotally and slidably connected to the table top by means of a rod extending between and rotatably connected to the upper ends of the legs and extending beyond the end of the leg into slots in members connected to the table top, the ends of said rod which lie in said slots being of greater thickness in one direction than in another and said slots being of a width less than the greater thickness of the ends of the rod and each having an enlarged part at the point reached by the end of the rod when the legs are in extended position, a bent plate welded on the middle part of said rod with its ends extending therefrom, and a bar extending between the legs close to said rod which as the legs are swung out to their extended position engages one end of said plate and applies pressure thereto to put the rod ends under torsional strain whereby when they enter the enlarged part of the slots they are turned to lock the legs in extended position, the other end of said plate serving as a finger-piece for turning the rod to unlock the legs, said finger piece end extending at such an angle and for such a distance from the rod that by movement thereof into engagement with the table top the rod ends are turned to position to slide in the slots.

WILLIAM P. DE SAUSSURE, JR.
